AUTOMATIC STARTER UNIT

Richard L. Appleton, Akron, Ohio, assignor of
one-third to Homer U. Montgomery and one-
third to Edward L. Rowland, Akron, Ohio

Application February 23, 1949, Serial No. 77,829

7 Claims. (Cl. 290—36)

1

This invention relates to self-perpetuating starting systems for internal combustion engines, such as for automotive vehicles.

In the past various attempts have been made to provide automotive vehicles with starting systems which ostensibly were intended to restart the engine should the same become stalled. Some of the prior art devices were operated to restart the engine after it had completely stalled and therefore full power of the starter motor was required to restart the engine. Some were also of such construction that proper adjustment and operation were materially affected by wear, varying weather conditions, or by other conditions.

One object of the present invention is to provide a starting system for internal combustion engines, which is self-perpetuating and substantially fool-proof to keep the engine running constantly, at all times while the ignition system for the engine is turned on.

Another object of the invention is to provide a starting system of the character described which renders the engine stall-proof in that it is automatically restarted upon the speed of the same being reduced to a predetermined extent below idling speed, whereby the engine is maintained in continuous running order without the usual drain on the battery due to restarting an engine after it has become stalled.

Another object of the invention is to provide a starting system of the character described which has little or no mechanically movable parts to become out of adjustment due to frictional wear or because of varying weather conditions.

These and other objects of the invention will be manifest from the following brief description and the accompanying drawings.

Of the accompanying drawings:

Figure 1 is a composite view, illustrating in perspective a unit of the system containing electromagnetic switches or relays, and in elevation a solenoid, the electromagnetic switch unit being partly broken away.

Figure 2 is a wiring diagram illustrating the system in connection with a starting motor, generator, and battery of an automotive vehicle engine, for example.

Referring particularly to Figure 2 of the drawing, the letter M indicates a starter motor for starting a combustion-type engine 10 of an automotive vehicle for example, the motor being connected from opposite sides thereof, in a motor circuit A, through leads 11 and 12 to a battery 13 of the type also usually provided in vehicles. Included in lead 11 is a switch S₁, which in inoperative condition of the starting system is open,

2

and which is adapted to be closed by energization of a solenoid C₁ associated therewith. Switch S₁ and solenoid C₁ combined may constitute a solenoid-type relay having, as an example, a 100 amp. rating on points. Closing of switch S₁ to the battery is effective to operate motor M to start the combustion engine (not shown), somewhat in the conventional manner. A generator G is operated to generate electricity in known manner by operation of the combustion engine, this generator being of the type used for a vehicle ignition and lighting system, for charging the battery, etc.

While a manually operable switch 16 may be connected between lead 12 and coil C₁ for closing the starting-motor switch S₁, improved means is provided herein for automatically operating motor M long enough to start the vehicle engine, and for perpetually keeping the engine running as long as the ignition switch 17 is closed in normal operation of the engine. Accordingly, ignition switch 17, which may be of known type adapted to be closed by turning a key, is connected in a starting circuit B in series with a starting switch S₂ and a holding-switch electromagnet C₃, said starting circuit being connected in parallel with the motor circuit A to battery 13. The electromagnet C₃ is arranged so that when energized it will close a holding switch S₃ which is connected in series with solenoid C₁ in a holding circuit C to battery 13, in parallelism with circuits A and B. That is, closing switch S₃ is effective through operation of solenoid C₁ to close switch S₁ and thereby operate the starting motor M. An independent holding circuit D, deriving power from residual current induced in generator 16 has leads 18 and 19 extending to opposite sides of the starting switch electromagnet C₂, whereby as soon as the motor M has been initially operated sufficiently to start the engine, residual current generated in generator G will energize starting-switch electromagnet C₂ to open starting-switch S₂ (see dotted lines in Figure 2), coil C₃ will be deenergized to open the holding switch S₃, which in turn will deenergize solenoid C₁ and open the motor switch S₁. Thus, as long as the combustion engine is not completely stalled, or is operating at a speed somewhat short of being stalled or above that speed, and current is accordingly flowing in holding circuit D, solenoid-operated switch S₁ will be open and the motor will be inoperative condition.

The electromagnets C₂ and C₃, with the co-operating switches S₂ and S₃ thereof, respectively, are in the nature of simple electromagnetic relays 21 and 22 of low amperage (say 2 or 3

amps.) which relays may be provided as a single encased unit 23, as shown in Figure 1. As many automotive vehicles are equipped with a suitable starting motor solenoid type relay, it may in some instances be possible to provide the above-described self-perpetuating starter system therein by the simple expedient of installing the encased unit 23 and wiring the same as shown in Figure 2.

In use of the starting mechanism described above, for continuous operation of the combustion engine of an automotive vehicle (not shown), the engine is initially started by the operator manually closing the ignition switch 17, as by means of the usual key, and thereby through starting switch S₂ energizing the holding-switch electromagnet C₃, which in turn closes the holding-switch S₃. This, through holding circuit C energizes solenoid C₁ therein, receiving current from the battery 13, to close motor switch S₁ and thereby operate the motor M in circuit A from battery 13, which starts said combustion engine in known manner. As soon as the engine is thus started it will generate sufficient current in the generator G to supply residual current in the independent generator circuit D, thereby energizing coil C₂ to open starting-switch S₂ in the starting circuit B. As long as there is residual current from the generator in circuit D the coil C₂ will hold the switch S₂ open in the manner described and the holding electromagnet C₃ will be maintained in deenergized condition to maintain the switch S₃ open, the coil C₁ deenergized, and the switch S₁ open.

Correspondingly, if at any time while the ignition switch 17 is closed the combustion engine attempts to stall, or operate at a speed sufficiently below idling speed, that the generator operated by the engine will have insufficient residual charge to energize the coil C₂, the starting-switch S₂ will automatically close circuit B, energize holding-coil C₃ to close switch S₃ in the holding circuit, and thereby through energization of solenoid C₁ close the switch S₁ to operate starting motor M for starting the combustion engine, as before. Thus, it will be seen that at all times while the ignition switch 17 is closed the system is self-perpetuating to maintain the combustion engine in running order. It will be observed also that because the system does not permit the combustion engine to become completely stalled, that is, it always restarts the engine while it is still turning over, and because the forward momentum of certain parts of the engine is utilized in restarting, no high current surge is drawn from the battery by the starting motor as would be the case where the starting motor is operated to start the combustion engine from a condition of rest thereof.

The system described above, while extremely simple, not only allows for maximum economy in use of the battery for restarting but is effective to keep the combustion engine in a continuous condition of operation in forward direction, at all times while the ignition switch 17 is closed.

Modifications of the invention may be resorted to without departing from the spirit thereof or the scope of the appended claims.

What is claimed is:

1. A self-perpetuating stall-proof electrical starting system for internal combustion engines, comprising a starter motor for starting the engine, battery means, and a normally open magnetically-operated motor switch in a motor circuit, motor switch electro-magnetic means for

operating said motor switch, a holding switch and a starting switch, said holding and starting switches each having electro-magnetic means for operating the same, a master switch, a generator operated by operation of said engine, a holding circuit having therein said motor switch electro-magnetic means and said holding switch, a starting circuit in parallelism with said motor circuit and having therein said holding-switch electro-magnetic means said starting switch and said master switch, and a generator circuit adapted to be electrically charged by the generator upon operation thereof by said engine, said generator circuit having therein said starting switch electro-magnetic means, whereby closing said master switch is initially effective through said starting switch to energize said holding-switch electro-magnetic means and by energizing said motor electro-magnetic means said motor switch for starting said motor, and whereby so long as said generator circuit is electrically charged by operation of the generator said starting switch will be held open by energization of the electro-magnetic means thereof and said holding and motor switches will be correspondingly opened by the respective electro-magnetic means thereof, the starting cycle of operation being self-operatively repeated as often as the generator charge is diminished a predetermined amount and the master switch is closed.

2. A self-perpetuating stall-proof electrical starting system for internal combustion engines, comprising a starter motor for starting the engine, battery means and a normally open magnetically operated motor switch in a motor circuit, motor switch electro-magnetic means for operating said motor switch, a normally open holding switch and a normally closed starting switch, said holding and starting switches each having electromagnetic means for operating the same, a manually operable switch, a generator operated by operation of said engine, a holding circuit having therein said motor-switch electro-magnetic means and said holding-switch, a starting circuit having therein said holding-switch electro-magnetic means said starting switch and said manually operable switch, and a generator circuit adapted to be electrically charged by the generator upon operation thereof by said engine, said generator circuit having therein said starting switch electro-magnetic means, whereby closing said manually operable switch is initially effective through said normally closed starting switch to energize said holding-switch electro-magnetic means and by energizing said motor electromagnetic means closing said motor switch for starting said motor, and whereby so long as said generator circuit is electrically charged by operation of the generator said starting switch will be held open by energization of the electro-magnetic means thereof and said holding and motor switches will be opened by deenergization of the respective electro-magnetic means thereof, the starting cycle of operation being self-operatively repeated as often as the generator charge is diminished a predetermined amount and the manually operable switch is closed.

3. A self-perpetuating stall-proof electrical starting system for internal combustion engines, comprising a starter motor for starting the engine, battery means and a normally open magnetically operated motor switch in a motor circuit, motor switch electro-magnetic means for

operating said motor switch, a holding-switch and a starting-switch, said holding and starting switches each having electro-magnetic means for operating the same, a manually operable switch, a generator operated by operation of said engine, a holding circuit in parallelism with said motor circuit and having therein said motor electro-magnetic means and said holding-switch, a starting circuit in parallelism with said motor circuit and having therein said holding switch electro-magnetic means said starting-switch and said manually operable switch, and a generator circuit adapted to be electrically charged by the generator upon operation thereof by said engine, said generator circuit having therein said starting-switch electro-magnetic means, whereby closing said manually operable switch is initially effective through said starting switch to energize said holding-switch electro-magnetic means and by energizing said motor electromagnetic means closing said motor switch for starting said motor, and whereby so long as said generator circuit is electrically charged by operation of the generator said starting switch will be held open by energization of the electro-magnetic means thereof and said holding and motor switches will be correspondingly opened by the respective electro-magnetic means thereof, the starting cycle of operation being self-operatively repeated as often as the generator charge is diminished a predetermined amount and the manually operated switch is closed.

4. A self-perpetuating stall-proof electrical starting system for internal combustion engines, comprising a starter motor for starting the engine, battery means and a normally open magnetically operated motor switch in a motor circuit, motor switch electro-magnetic means for operating said motor switch, a normally open holding switch and a normally closed starting switch, said holding and starting switches each having electro-magnetic means for operating the same, a manually operable switch, a generator operated by operation of said engine, a holding circuit in parallelism with said motor circuit and having in series therein said motor electro-magnetic means and said holding switch, a starting circuit in parallelism with said motor circuit and having in series therein said holding-switch electromagnetic means said starting switch and said manually operated switch, and a generator circuit adapted to be electrically charged by the generator upon operation thereby by said engine, said generator circuit having therein said starting-switch electro-magnetic means, whereby closing said manually operable switch is initially effective through said normally closed starting switch to energize said holding-switch electro-magnetic means and by energizing said motor electro-magnetic means closing said motor switch for starting said motor, and whereby so long as said generator circuit is electrically charged by operation of the generator said starting switch will be held open by energization of the electro-magnetic means thereof and said holding and motor switches will be opened by de-energization of the respective electro-magnetic means thereof, the starting cycle of operation being self-operatively repeated as often as the

generator charge is diminished a predetermined amount and the manually operated switch is closed.

5. A self-perpetuating stall-proof electrical starting system for internal combustion engines, comprising a starter motor for starting the engine, battery means and a normally open magnetically operated motor switch in a motor circuit, motor switch electro-magnetic means for operating said motor switch, a normally open holding switch and a normally closed starting switch, said holding and starting switches each having electro-magnetic means for operating the same, a manually operable switch, a generator operated by operation of said engine, a holding circuit in parallelism with said motor circuit and having therein said motor electro-magnetic means and said holding switch, a starting circuit in parallelism with said motor circuit and having therein said holding switch electro-magnetic means said starting switch and said manually operable switch, and a generator circuit adapted to be electrically charged by the generator upon operation thereof by said engine, said generator circuit having therein said starting switch electro-magnetic means, whereby closing said manually operable switch is initially effective through said normally closed starting switch to energize said holding-switch electro-magnetic means and by energizing said motor electro-magnetic means closing said motor switch for starting said motor, and whereby so long as said generator circuit is electrically charged by operation of the generator said starting switch will be held open by energization of the electro-magnetic means thereof and said holding and motor switches will be opened by deenergization of the respective electro-magnetic means thereof, the starting cycle of operation being self-operatively repeated as often as the generator charge is diminished a predetermined amount and the manually operated switch is closed.

6. A mechanism as set forth in claim 5, said motor switch electro-magnetic means including a solenoid, and said holding and starting switch electro-magnetic means including electro-magnets.

7. A mechanism as set forth in claim 5, including selectively operable switch means connected in series with said motor switch electro-magnetic means directly to said battery, for closing said motor switch to operate the motor without going through said starter and holding circuits.
